DRILLING AND TAPPING MACHINE

Eric J. Stahlhammer, Bridgeport, Conn., assignor
to The Bodine Corporation, Bridgeport, Conn.,
a corporation of Connecticut

Application November 29, 1933, Serial No. 700,241

22 Claims. (Cl. 10—136)

This invention relates to drilling and tapping machines, especially multispindle machines in which a drill or tap carried by one spindle operates on one piece of work while the other tool carried by another spindle operates on the same or another piece of work, the work being usually progressively moved or indexed into position to be engaged by the tools. In its more specific aspects, the invention relates to the operation of such a machine hydraulically.

An object of this invention is the provision of a drilling and tapping machine which is strong and sturdy in construction, so that it may perform heavy work, considering its size and weight, and yet be economically constructed, easily set up and adjusted for different kinds of work, and reliable in operation.

Such machines comprise a suitable frame, a source of power, means for rotating or driving the tools, means for moving the work and the tool toward and from each other, which will be hereinafter called the feeding means, and means for progressively carrying pieces of work into position to be operated upon by the tools, hereinafter referred to as indexing, and certain other related mechanism.

One of the features of this invention is the provision of a reciprocating carriage which not only operates the driving means but also controls the feeding means and the indexing means. In the disclosed form of the present invention, this carriage comprises a rack for engaging gears forming part of the driving train, and it carries cams for controlling the feeding movements of the tool. It also carries devices for controlling the indexing mechanism as well as devices for determining the length of stroke of the carriage. The carriage is located in an easily reached position, and the cams and devices above referred to are adjusted on the carriage from the front of the machine so that the setting-up of the machine to do a particular job is comparatively easy.

In the preferred form of the present invention, the carriage is operated by a fluid-operated motor, and the movements of the carriage are controlled by a valve operated directly or indirectly by the adjustable devices, above referred to as being carried by the carriage.

In the preferred form of the present invention, the indexing mechanism is also operated hydraulically, and the valve mechanism for controlling the indexing is located adjacent the carriage to be operated by the devices carried by the carriage.

Others of the more important features of this invention comprise the provision of means for regulating the hydraulic pressure applied to the fluid motor for driving the rack, the valve mechanism for controlling the fluid motor, the valve mechanism for controlling the indexing, the locking of the work support in adjusted position hydraulically, and the arrangement whereby locking and indexing mechanism are operated automatically in coordination, and other features and advantages which will hereinafter appear.

In the accompanying drawings—

Fig. 1 is a side elevation of a drilling and tapping machine made according to the present invention, in its present preferred form.

Fig. 2 is a vertical sectional view taken through the middle of the machine shown in Fig. 1.

Fig. 3 is a front elevation of the machine shown in Fig. 1, with the hood which extends over the driving train shown in section.

Fig. 4 is a vertical sectional view through the upper part of the frame, the carriage, and the valve mechanism for controlling the fluid motor.

Fig. 5 is a front view of the valve actuating mechanism showing the feed control cam, and means for adjustably supporting it on the carriage, the actuating mechanism being in position to move the valve lever.

Fig. 6 is a view similar to Fig. 5, showing the valve lever released and operated.

Fig. 7 is a front view of the valve and valve actuating mechanism.

Fig. 8 is a sectional view taken on line 8—8 of Fig. 4, showing the valve and the fluid operated motor.

Fig. 9 is a sectional view of the valve device for controlling the indexing.

piston for operating the indexing lock plunger.

Fig. 17 is a detail sectional view of the valve shown in Fig. 15.

Fig. 18 is a similar view, looking at the parts from the other side.

Fig. 19 is a diagrammatic view showing the manner in which the various parts of the device are connected together hydraulically.

Fig. 20 is a sectional view of the pressure regulating valve shown in Fig. 19.

Fig. 21 is a sectional view of the safety valve shown in Fig. 19.

Fig. 22 is a vertical sectional view through the relief valve employed to avoid the shock and vibration incident to the reversing of the carriage at the end of its movement toward the right.

As shown in the accompanying drawings, the drilling and tapping machine of the present invention comprises a frame 10 having a base 11 from which it rises vertically. The frame 10 is hollow and its lower portion constitutes a reservoir 12 for the fluid employed to transmit power from one point on the machine to another. The fluid used is preferably an oil, because it not only transmits power from one point to another on the machine but lubricates the operating parts with which it contacts. Within the hollow frame 10 and mounted on a removable back plate 13 is an electric motor 14 having a drive shaft 15 connected to a pump 16 also secured to the removable back plate 13. The pump 16 has an inlet pipe 17 extending down into the oil reservoir 12 and an outlet pipe 18 connected to the various fluid motors employed in the operation of the machine.

The casing has a side door 19 by means of which access to the motor may be had for oiling, inspection, etc. By having the motor and pump mounted on the back plate 13, when the latter is removed these parts come out of the frame 10 as a unit.

The front part of the frame 10 is provided with ways 20 on which a worktable 21 is slidably mounted and may be secured in desired position by operation of a clamp 22. To sustain the greater part of the weight of the worktable 21, the frame is provided with a vertical screw 23 having a handwheel 24 by means of which the frame may be raised and lowered when the clamp 22 is released.

The work, which may be of any desired character, may be fed to position to be operated upon in any suitable or conventional way, that is to say, the work may be advanced on a drum, on a conveyor, or, as shown herein, on a turntable or dial 25. The dial or other work support is, of course, provided with suitable fixtures for holding the work in desired position and it is rotated step-by-step in a manner hereinafter explained to bring pieces of work successively into operating position and progressively from one tool to another.

The worktable may be provided with a tray 26 adjustably supported on an extension 27 on which a supply of work to be done may be supported in convenient position for the operator to insert in the proper places on the dial 25. As shown, the tray 26 may also be adjusted horizontally, for its depending flanges 28 are slidably mounted on a horizontal portion 29 of an L-shaped piece 30 and are adjustably secured to the horizontal piece 29 by screws 31. The worktable further has a draw 32 for receiving the chips thrown off by the worktable.

The working tools T, which may include taps, drills, counterbores, etc., are carried by chucks 33 on spindles 34 mounted in bearings 35 having ears 36 which may be clamped to segmental mounting arms 37 which extend out from a vertically extending auxiliary frame or slide 38. Bolts 39 secure the spindle bearing arms 36 to the extension 37, and, at the same time, secure arcuate arms 40 to the extensions 37. These arms 40 are employed to support other spindles 10 if and where needed.

While it is within the scope of this invention to have the work move up and down relative to the tool, in the preferred form of this invention herein disclosed, the slide 38 carrying the spindles 34 is moved up and down to feed the tool toward and from the work. The means for accomplishing this will be described below.

Tool drive

The spindles 34 for the tools T have gears 41 at their upper ends. These engage with suitable intermediate gears 42 which ultimately engage a gear 43 carried by a shaft 44 having its lower end supported in a bearing 45 carried by the slide 38. The upper end of the shaft 44 engages a bearing 46 carried by the upper portion 47 of the slide 38. Between the bearings 45 and 46, the shaft 44 has a barrel pinion 48 which engages with a driving member herein-after referred to. The upper end 47 of the slide 38 is provided with a post 49 sliding in a bearing 50 carried by a bracket 51 attached to the main frame.

As above pointed out, one of the important features of this invention is the provision of a reciprocating carriage which not only drives the tools but also controls the feeding of the tools and work. This carriage, in the form of the invention herein disclosed, comprises a horizontal bar 52, a rack 53, a rod 54, and end pieces 55 securing said rods and rack together in parallel relation. The carriage is guided for movement horizontally in a plane intersecting the axis of the drive shaft 44, and to this end the upper portion of the main frame is provided with rollers 56 engaging the rear side of the rack 53. The rod 54, as shown in Fig. 8, carries on its center portion a piston 58 slidably mounted in a cylinder 59 of a double-acting fluid operated motor 60 by means of which the carriage is reciprocated.

The rack 53 engages and drives the barrel pinion 48 and the latter is made long enough so that the driving engagement between the rack and the pinion is maintained even though the pinion travels up and down with the slide 38. The length of stroke of the carriage and rack determines the amount of rotation of the drive shaft and hence the extent of rotation of the tools T.

The present invention provides means traveling with the carriage C for regulating the stroke of the carriage and determining at what points in its travel its direction was to be reversed. For this and other purposes, in the embodiment of the invention herein disclosed, there are two controllers 61, one at each end of the carriage.

These are slidably mounted on and are keyed to the rod 52 (see Fig. 4) and are provided with a clamping screw 62 and handle 63 by means of which the screw may be tightened against the rod 52 to hold the controller with which it is associated in the position to which it may be adjusted along the rod 52.

According to the present invention, the adjustable controllers 61 may operate any suitable mechanism for causing the carriage to stop at a predetermined point and then reverse its direction of travel. However, since, in the embodiment of the invention shown herein, the carriage C is reciprocated by the double-acting fluid motor 60, the controllers 61 are here employed to operate a stopping and reversing valve 64 (see Figs. 4 to 8).

The reversing valve 64 comprising a housing 65 having a manifold 66 provided with an inlet pipe 67 and two outlet pipes 68 and 69 adapted to be connected to opposite ends of the cylinder 59. Within the housing 65 there is a cylindrical chamber 70 containing a rotary valve 71 having bearings in the housing 65 and in a cover plate 72 for the housing. This rotary valve has a shaft 73 carrying an operating arm 14 which extends into position to be engaged and operated by the controllers 61.

The rotary valve 71 has two definite positions in the cylindrical chamber 70 determined by shock absorbing stops 15 mounted on the cover plate 72. The valve 71 has a central channel 76 communicating with two branches 77 and 78 adapted to alternately communicate with ports 79 and 80 of conduits, preferably formed integral with the housing 65 and leading to opposite ends 30 of the cylinder 59.

In addition, the valve 71 has another pair of channels and ports 81 and 82 cooperating with the outlet orifices 68 and 69 respectively. In one position of the valve, for instance that shown in Fig. 8, the central port 76 being in communication with the feed pipe or inlet 67 transmits fluid under pressure through the channel 78 to the port 80, and thus to the right-hand side of the cylinder 58. At the same time, the channel 81 at the opposite side of the valve is in communication with the outlet pipe 68 and also is in communication with the port 79 leading to the left-hand side of the cylinder, allowing the fluid therein to escape through the outlet pipe 69. When the valve arm 14 is rocked to move the valve clockwise from the position shown in Fig. 8, the channel 77 is brought into communication with the port 79, the channel 78 is closed by the housing 65, and the channel 82 is connected to the port 80, with the result that fluid under pressure passes through the port 79 and into the left-hand side of the cylinder and the fluid in the right-hand side escapes through the port 80 and channel 82 to the outlet pipe 69, causing the piston 58 and rod 54 to be stopped and then moved to the right.

In order that the carriage C may be stopped and reversed quickly at exactly the right point in its travel, the valve arm 14 is operated, according to the present invention, with a snap action. For this purpose, each controller 61 carries a plunger 83 in position to engage a sleeve 84 on the end of the arm 14 and tend to operate it. However, in each of its operating positions, the arm 14 is locked against movement by a locking pin 85 (see Figs. 4, 5 and 6) slidably mounted in the sleeve 84 and spring-urged to engage a locking piece 86 secured to the valve housing cover 72.

Since it cannot move the arm 14 immediately, the plunger 83 moves relative to the controller 61 and tensions a spring 87 contained within it, thus storing up power to be subsequently employed to move the arm. As the plunger 83 is being energized, a releasing finger

88 carried by the controller 61 approaches a knob 89 on the locking pin 85. At the proper time, the releasing finger begins to withdraw the locking pin 85 from the locking piece 86, and the controller 61 is set so that at just the right moment the pin 85 will be completely withdrawn and the valve arm 14 will be allowed to move under the influence of the plunger 83 to the other position, the right, as shown in Figs. 5 and 6, with a snap action. The shock of this rapid movement of the arm 14 is absorbed by the shock-absorbing stops 15, and the locking pin 85 engages the other side of the locking piece 86 to hold the valve arm 14 in that position.

It is contemplated by this invention that one of the controllers 61 may be fixed and incapable of adjustment, for the adjustment of a single controller will lengthen or shorten the stroke of the carriage C. However, to permit the points in the travel of the carriage at which reversing takes place and at which the wear of the rack is maximum to be varied, it is preferable that both controllers 61 be made adjustable relative to each other and to the carriage C.

Tool and work feeding

According to the present invention, the carriage C also controls the feeding movements of the tools. For this purpose, the post 49 at the upper end of the slide 38 is provided with a collar 90 having a roller 90 in position to be engaged by cams mounted on and traveling with the carriage C.

In the form of the invention herein disclosed, there are two cams 92 and 93, and these are carried by the controllers 61. The cam 93 is on the right-hand controller 61 and has a sharp rise which causes or permits rapid movement of the slide 38. The cam 93 has a pair of slots 94 through which extend screws 95 used to secure the cam 93 to the controller 61. These slots 94 extend parallel to the direction of travel of the carriage and permit the cam 93 to be adjusted longitudinally of the carriage independently of the controller, so that the point at which movement of the slide 38 begins and ends may be varied. This cam 93 is intended to control the movements of the carriage during tapping operations.

The cam 92, in the form of the invention herein disclosed, forms a continuation of the cam 93 and is hinged to it at 96 and has its other end provided with a vertical slot 97 through which passes a screw 98, (see Fig. 5) by means of which this end of the cam is fastened to the left-hand controller 61. The vertical slot 97 permits vertical adjustment of the end of the cam 92 and this movement may be regulated by an adjusting screw 99 carried by the left-hand controller 61. The cam 92 is intended to control movements of the slide 38 during the drilling operation and is designed to regulate the extent of downward movement of the slide very accurately, so that a closed-bottom hole in a work-piece may be tapped just to the proper depth, and so that this may be done without resetting the position of the tool in the holder or work-table.

It is within the scope of this invention to have the cams 92 and 93 actually move the slide 38 both upwardly and downwardly. However, since the tool spindles themselves are usually each yieldingly and resiliently pressed against the work so as to descend as the work progresses

regardless of the speed at which the slide 38 descends, the present invention provides the slide 38 with springs 100 normally tending to pull them down. Thus, when the carriage C moves from left to right, the slide 38 is allowed to descend under the influence of the springs 100 and at a rate depending upon the inclination of the cams 92 and 93. On the return stroke of the carriage, however, that is, when the carriage moves from right to left, the cams 92 and 93 engage the roller 91, positively lifting the slide 38 against the tension of the springs 100.

For many purposes, it is sufficient to use the cam 93 alone, and in such cases the cam is carried solely by, and is adjustable as a unit with, the right-hand controller 61. Of course, it should be understood that the cams 92 and 93 may be given any suitable or desirable shape, depending upon the way that the tools are to be fed to the work, and, since they are removably carried by the controller or the controllers, a separate cam can be made for each job to be done on the machine.

As shown in Figs. 2 and 3, the load on the slide 38 and parts mounted thereon is not borne directly by the rod 52 on which the controller 61 is mounted. Instead, the controller is provided with a rail 101 resting on a roller 102 carried on an arm 103 on the main frame and located directly under the roller 91 on the slide frame 38. Hence, the weight of the frame 38 is transmitted through the cam 93, controller 61 and rail 101 to the roller 102 and the main frame.

It should be noted that in setting up the machine, the mechanic, after locating the spindle brackets 35 in desired positions, securing them to the slide 38, and connecting up the intermediate gearing, may, while still standing in front of the machine, regulate the extent of feed of the tool slide 38 by merely reaching up and adjusting the position of the cam 93 on the right-hand controller 61. The point in the cycle of operations at which the slide 38 begins to move may be regulated by loosening the clamp 62-63 of the right-hand controller 61 and adjusting it longitudinally along the rod 52. At the same time, if any adjustment of the position of the worktable 25 is desired, this may be accomplished by reaching down and turning the hand-wheel 24. The point at which the drive is to be reversed at the end of the downward movement of the table 38 may be fixed and determined by loosening the clamp 62-63 on the left-hand controller 61 and adjusting it along the rod 52 to the desired position. If it is desired to raise the lower limit of movement of the tool slide 38, the mechanic may merely reach up and adjust the end of the cam 92 by means of the adjusting screw 99.

Thus, according to the present invention, it is unnecessary for the mechanic setting up the machine to go around to the back or to the side 65 of the machine to make adjustments changing the extent or timing of the feeding operations.

Indexing

According to the present invention, the means 70 for moving the worktable 25 step-by-step is also hydraulically operated. This turntable 25 is provided with a shaft 104 having an index wheel 105 secured thereto.

Also mounted on the shaft 104 is an arm 106 75 provided with a pawl 107, the end of which en-

gages teeth 108 in the index wheel. The pawl is held in position to enter between the teeth 108 by a spring 109 and the pawl arm is returned to normal position after being operated by a spring 110.

For the purpose of operating the pawl arm and thus moving the turntable 25 step-by-step, a cylinder 111 mounted adjacent the index wheel 105 is provided with a piston 112 and a piston rod 113, the end of which extends out through the cylinder and is in position to engage the end of the pawl arm 106. Instead of directly engaging the arm 106, the piston rod 113 engages a screw 114 adjustably mounted on the end of the arm 106.

The indexing wheel 105 is locked in its positions of rest by a dog 115 which enters between the teeth 108. This dog is on the end of a piston rod 116 carrying a piston 117 located in a cylinder 118. As shown in the accompanying drawings, the cylinders 111 and 118 are connected together as a unitary structure and are operated coordinately by hydraulic pressure.

For this purpose, the cylinders 111 and 118 are connected together by a pipe or conduit 119 leading from the lower part of the former to the upper part of the latter as viewed in Fig. 19, and another pipe or conduit 120 leading from the upper part of the cylinder 111 to the lower part of the cylinder 118. This same part of the cylinder 118 is connected by pipes 121-122 to an indexing control valve 123, while the conduit or pipe 119 is connected by pipes 124-125 to the other side of the indexing control valve 123.

Between the pipes 121 and 122, and 124 and 125 are extensible connections 122a and 125a respectively, to permit the vertical movement of the worksupport 21 the dial 25 and the indexing mechanism relative to the pipes 122 and 125 leading to the control valve 123 which is mounted on the stationary part or main frame of the machine.

In the broader aspects of this invention, any suitable control valve may be employed which will cause the fluid under pressure flowing through the pipes 122 and 125 to be reversed in its direction of flow. As diagrammatically illustrated in Fig. 19, the movement of the fluid under pressure is indicated by the arrows, and leaving the valve 123 flows down from the pipes 122 and 121 into the lower part of the cylinder 118 where it forces the piston 117 and rod 116 outwardly causing the dog 115 to lock the index wheel 105 against rotation. The fluid then passes through the lower end of the cylinder 118 into the pipe or conduit 120 and into the upper end of the cylinder 111, where it has forced the piston 112 and piston rod 113 inwardly of the cylinder allowing the spring 110 to retract the pawl arm 106.

In so moving the parts, the fluid on the upper side of the piston 117 and on the lower side of the piston 112 escapes through the pipe 119 and pipes 124 and 125 back to the control valve 123.

When the direction of flow is reversed, however, the fluid will flow from the valve 123 through the pipes 125-124 into the pipe or conduit 119 and from this into the upper part of the cylinder 118 and the lower part of the cylinder 111, with the result that the piston 117 will move inwardly and withdraw the locking dog 115 from the index wheel, and the piston 112 will move outwardly driving the pawl arm to advance the index wheel 105 and dial 25. At 75

the same time, the fluid on the other side of the two pistons, namely, the top of piston 112 and the bottom of piston 111, will be permitted to escape through the pipes 120, 121 and 122.

5 When the valve 123 is reversed at the end of the indexing operation in a manner hereinafter described, it is desired that the locking dog 115 engage the index wheel 105 before the pawl arm 106 begins to return so that it will not drag the 10 index wheel 105 back with it. In order to insure this, the pipe or conduit 120 is interrupted at some portion between the cylinders 111 and 112, and at the interruption is provided with a pressure regulating valve 126, shown in detail in 15 Figs. 17 and 18.

In the specific embodiment of the invention herein disclosed, part of the conduit 120 is formed by a channel 127 in the piece making up the cylinder 111 and the regulating valve 126 20 is located to interrupt this channel. The valve comprises a movable or plunger portion 128 sliding in a cylinder 129 and normally urged upwardly by a spring 130, the lower end of which engages an adjustable cap or screw 131. The 25 upper end of the plunger 128 has a knife edge 132 engaging a seat 133 and bleed openings 134 permit the flow of some fluid past this valve at all times. The spring 130 is set, however, so that the full amount of fluid will not pass 30 through the channel 127 until sufficient pressure has been produced therein after the moving into operative position of the locking dog 115 and its piston 117, at which time the plunger 128 is forced down from its seat 133 and allows 35 the fluid to pass on through the channel 127 into the cylinder 111 to act on the piston 112 and permit the return of the pawl arm 106.

The plunger 128 has holes 135 drilled therethrough so that any fluid which might seep 40 into the cylinder within which the plunger moves may escape upwardly and outwardly through the holes 135.

This coordination of the index wheel lock 45 and feed arm may, of course, be done mechanically, but when accomplished hydraulically, as herein disclosed, the use of much complicated mechanism is avoided and the functions are performed by the simple pressure regulating valve 126.

50 As stated above, the indexing control valve 123 may be of any suitable type and construction, and may be operated in any suitable way. However, according to the present invention, the control valve is operated by means carried by the right-hand controller 61. For this purpose, the controller 61 is provided with an extension 136 having an arm 137 carrying a cam 138 (see Figs. 3 and 19), and the control valve 123 is mounted on the main frame along side 55 the cylinder 59 to be in position to be operated by the cam 138 when the carriage C reaches the end of its movement toward the left.

As shown in Figs. 9 to 13, the valve 123 has a housing 139 provided with a top plate 140 and 60 a bottom plate 141, and these parts form between them cylinder chambers 142 and 143 in which are mounted pistons 144 and 145. The cylinders 144 and 145 are connected together for movement in opposite directions simultaneously by a lever 146, whose end engages in slots 147 in the pistons 144 and 145. The piston 145 is normally urged downwardly by a spring 148, the upper end of which is located in a housing 148a.

75 Thus, the pistons are biased to normally oc-

cupy the position shown in Fig. 9. The lever 146 is mounted on a shaft 149 which extends out through the housing and has an arm 150 provided with a roller 151.

This roller 151 normally lies in a position to be engaged by the cam 138 shown in dot-and-dash lines in Fig. 9, and when engaged by the cam is rocked counterclockwise with the result that the piston 144 is depressed and the piston 145 rises against the tension of the spring 148. 10 When the cam 138 recedes from the roller 151, the spring 148 returns the parts to the position shown in Fig. 9.

The pipes leading to the control valve are arranged in manifold form in a manifold 152, 15 and the conduits in this manifold are given the same reference numerals as the pipes in the diagrammatic illustration of the system shown in Fig. 19. Accordingly, the conduit or channel 125 leads to the cylinder 142, while the conduit 20 or channel 122 leads to the cylinder 143. Between these two channels is another channel 153 which leads from the control valve 123 to the pipe 18 and pump 16.

Fluid under pressure flows through the channel 153 and may then flow to the right or to the left through an auxiliary channel 154 to the piston 144 or 145. With the parts in the position shown in Figs. 9 to 13 and 19, fluid under pressure flows from the channel 154 into 30 an annular groove 155 in the piston 145, and since this annular groove is in communication with the channel 122 at this time, fluid flows in the direction of the arrows shown in Fig. 19. At the same time, a cut-away portion or port 35 156 in the piston 144, the lower end of which is hollow, is located opposite the opening of the channel 125, and the fluid rising in the pipe 125, as shown in Fig. 19, flows into the hollow end of the piston 144 and then downwardly into a horizontal channel 157 located below the piston. This channel 157 connects with a channel 40 and pipe 158 leading to the reservoir 12.

When the cam 138 engages the roller 151 and rocks the arm 150 and shaft 149 and reverses 45 the positions of the pistons from that shown in Fig. 9, the channel 122 is connected to the outlet channel 157 by the hollow cut-out lower portion of the piston 145, and the channel 154 is connected with the channel 125 by the annular groove 155 in the piston 144, with the result 50 that the direction of flow of the fluid is reversed. This causes the dog 115 operated by the piston 117 to disengage the index wheel 105 after which the feed arm 106 is returned by the 55 piston 112.

In order to cause the indexing and locking devices to operate before sufficient pressure is applied to the driving piston 58 to cause movement thereof, a pressure regulating valve 159 is interposed between the main feed pipe 18 and 60 the pipe 67 leading to the valve 64. This valve 159 is illustrated in detail in Fig. 21. It comprises a housing 160 in which is located a valve 161 having a bleed port 162 allowing some fluid 65 to escape past the valve at all times. The valve is normally pressed down on its seat by a spring 163 and the upper end of the spring is engaged by a screw cap 164 threaded in the housing 160. By rotating the screw cap 164, 70 the tension of the spring may be increased or decreased, thereby determining at what pressure the valve 161 will open and permit passage of the fluid to the pipe 76. A cap 165 threaded on the cap 164 serves to conceal the cap and 75

acts as a lock nut to prevent its casual movement.

A safety valve 166, constructed substantially the same as the valve 159, is connected to the pipe 76 and has an outlet pipe 167 leading back to the reservoir 12. Thus, when the fluid in the system exceeds the predetermined pressure, the surplus escapes through the valve 166 and outlet pipe 167.

10 When the carriage C is at the end of its movement toward the right and while the valve 64 is shifting from one position to another, there is a time when fluid under pressure is applied to both ends of the cylinder and both 15 sides of the piston, with the result that the piston is stopped with a hammer blow producing shocks and vibrations which are undesirable. To avoid this difficulty, the present invention provides a relief valve 168 shown in Fig. 19 and shown in detail in Fig. 22. This relief valve has a housing 169 provided with a piston-like valve 170 normally urged downwardly by a spring 171, the upper end of which engages a perforated wall 172 in the housing. 20 The end of the valve 170 extends through a gland 173 in position to be operated by a cam 174 carried by the left-hand controller 61. The valve 170 has a portion 175 normally closing a port 176 in the housing connected to a pipe 30 or conduit 177 opening into the pipe 79, leading to the left-hand side of the cylinder 59. The upper end of the valve housing 169 is provided with an outlet 178 connected to a pipe 179 opening into a pipe 180 joined to the outlet pipes 35 68 and 69 which is controlled by the valve 64.

When the carriage reaches its extreme right-hand position, the cam 174 lifts the valve 170 so that the fluid under pressure in the pipe 177 may pass into the valve through an annular 40 recess 181 therein. Fluid may then flow upwardly through small apertures 182 in the valve and through the perforated wall 172. Here, however, it is stopped by a pressure regulating valve 183 backed by a spring 184 having an 45 adjustable cap 185 and a cover cap 186. The fluid cannot escape past the pressure regulating valve 183 except when it is under abnormal pressure due to the fact that the fluid is being applied to both sides of the piston 58. 50 When this abnormal pressure is such that it would cause the piston 58 to be stopped abruptly, the fluid may escape past the valve 183 into the return pipe 180.

Of course, the relief valve 168 may be provided, if desired, for both ends of the piston's travel, but it is not necessary, in the embodiment of the invention herein disclosed, because at the time that the piston 58 and carriage C reach the end of their travel toward the left, 55 the indexing mechanism begins to operate, and this so reduces the pressure of the fluid as to prevent the hammer blow above referred to.

Variations and modifications may be made within the scope of this invention and portions 60 of the improvements may be used without others.

Having thus described the invention, what is claimed as new and for which it is desired to obtain Letters Patent, is:—

70 1. In a drilling and tapping machine, the combination of a work-holder; a tool-holder; a tool driving shaft; a pinion on said shaft; a carriage mounted to reciprocate in a plane intersecting the axis of said shaft; a rack on said 75 carriage engaging and driving said pinion; re-

versible power means connected to said carriage to reciprocate the same; and means, including means traveling with said carriage, for automatically reversing the action of the power means at the ends of travel of the carriage. 5

2. In a drilling and tapping machine, the combination of a work-holder; a tool-holder; a tool driving shaft; a pinion on said shaft; a carriage mounted to reciprocate in a plane intersecting the axis of said shaft; a rack on said carriage engaging and driving said pinion; reversible power means connected to said carriage to reciprocate the same; and means, including means traveling with said carriage, for automatically stopping and reversing the action of the power means at the ends of travel of the carriage, said last-named means comprising adjustable devices, one mounted at each side of the carriage and each adjustable along the carriage to vary the points in the travel of the latter at which its movement is stopped and caused to reverse. 10

3. In a drilling and tapping machine, the combination of a work-holder; a tool-holder; a tool driving shaft; a pinion on said shaft; a carriage mounted to reciprocate in a plane intersecting the axis of said shaft; a rack on said carriage engaging and driving said pinion; means for producing relative feeding movements of the work-holder and tool-holder toward and from each other, said means including a reciprocating slide on which one of said holders is mounted, and a cam traveling with said carriage and engaging said slide to control the feeding movements thereof; reversible 30 power means connected to said carriage to reciprocate the same; and means, including means traveling with said carriage, for automatically reversing the action of the power means at the ends of travel of the carriage. 35

40 4. In a drilling and tapping machine, the combination of a work-holder; a tool-holder; a tool driving shaft; a pinion on said shaft; a carriage mounted to reciprocate in a plane intersecting the axis of said shaft; a rack on said carriage engaging and driving said pinion; means for producing relative feeding movements of the work-holder and tool-holder toward and from each other, said means including a reciprocating slide on which one of said holders is mounted, and a cam traveling with said carriage and engaging said slide to control the feeding movements thereof, said cam being adjustable along the carriage to vary the relative movements of the tool-holder and the work-holder 45 in relation to the traveling movements of the carriage; reversible power means connected to said carriage to reciprocate the same; and means, including means traveling with said carriage, for automatically stopping and reversing the action of the power means at the ends of travel of the carriage, said last-named means comprising adjustable devices, one mounted at each side of the carriage and each adjustable along the carriage to vary the points in the 50 travel of the latter at which its movement is stopped and caused to reverse. 55

5. In a drilling and tapping machine, the combination of a frame; a tool-holder; a work-holder; means for producing relative feeding movements of the tool-holder and work-holder toward and from each other including a slide on which one of said holders is mounted; a carriage mounted to travel at right angles to the direction of movement of the slide; a cam on 60 65 70 75 80 85 90 95 98 99 100

the carriage engaging the slide to control the feeding movements of the latter; reversible power means connected to said carriage to reciprocate the same; and means, including means 5 traveling with the carriage, for controlling the direction and extent of operation of the carriage.

6. In a drilling and tapping machine, the combination of a frame; a tool-holder; a work-holder; means for producing relative feeding 10 movements of the tool-holder and work-holder toward and from each other including a slide on which one of said holders is mounted; a carriage mounted to travel at right angles to the direction of movement of the slide; a cam on the 15 carriage engaging the slide to control the feeding movements of the latter; a double acting fluid operated motor for reciprocating said carriage; and means, including a reversing valve and operating means therefor, in part mounted on the 20 carriage and in part mounted on the frame, for controlling the direction and extent of operation of the carriage.

7. In a drilling and tapping machine, the combination of a tool-holder; a work-holder; means 25 for resiliently feeding one of said holders toward the other to do work; means for rotating the tool-holder; and a fluid operated element for simultaneously operating the rotating means and permitting said resilient feeding means to operate.

8. In a drilling and tapping machine, the combination of a frame; a tool-holder; a work-holder; means for rotating said tool-holder; means for indexing the workholder to bring pieces of work successively into position to be 30 operated upon by a tool in the tool-holder; and fluid operated means for supplying power to and rotating said rotating means and operating said indexing means alternately and in coordination.

9. In a drilling and tapping machine, the combination of a tool-holder; a work-holder; means 40 for feeding one of said holders toward and from the other independently of the rotation of the tool holder; means for rotating said tool-holder; means for indexing the work-holder to bring pieces of work successively into position to be 45 operated upon by a tool in the tool-holder; a fluid motor for supplying power to and operating said feeding means and rotating means simultaneously and in coordination; a separate fluid motor for operating the indexing means alternately with said feeding and rotating means; and means for controlling said motors for coordinate 50 operation.

10. In a drilling and tapping machine, a reciprocating power transmitting carriage; a double-acting fluid motor operating said carriage; a source of fluid pressure; a reversing valve connecting the source of fluid pressure to said fluid motor; an operating arm on said valve; means 55 for locking the arm in right and left hand positions; yielding means traveling with the carriage and becoming operative near the end of travel of the carriage to tend to rock said arm; and means traveling with the carriage to release the lock suddenly at the end of travel of the carriage and permit said yielding means to rock said arm and reverse the direction of drive of the fluid motor and carriage.

11. In a drilling and tapping machine, the combination of a frame; a tool-holder; a work-holder; means for producing relative feeding 60 movements of the tool-holder and work-holder toward and from each other including a slide on which one of said holders is mounted; a carriage mounted to travel at right angles to the

direction of movement of the slide; a cam on the carriage engaging the slide to control the feeding movements of the latter; a double acting fluid operated motor for reciprocating said carriage; means, including a reversing valve and 5 operating means therefor, in part mounted on the carriage and in part mounted on the frame, for controlling the direction and extent of operation of the carriage; and means for relieving the pressure of the fluid on one side of the 10 motor during the reversing operation thereof.

12. In a drilling and tapping machine, the combination of a frame; a tool-holder; a work-holder; means for producing relative feeding 15 movements of the tool-holder and work-holder toward and from each other including a slide on which one of said holders is mounted; a carriage mounted to travel at right angles to the direction of movement of the slide; a cam on the carriage engaging the slide to control the 20 feeding movements of the latter; a double acting fluid operated motor for reciprocating said carriage; means, including a reversing valve and operating means therefor, in part mounted on the carriage and in part mounted on the frame, 25 for controlling the direction and extent of operation of the carriage; and means for relieving the pressure on one side of the motor during the operation of the reversing valve, said means including a valve operated by the reciprocating carriage and connected to the fluid operated motor to bypass the fluid at one side of the piston when under excess pressure incidental to the operation of the reversing valve.

13. The invention as defined in claim 5, in 30 which the cam for controlling the feeding movements of the slide is adjustable longitudinally relative to the carriage and to the controlling means thereon.

14. The invention as defined in claim 5, in 40 which the cam for controlling the feeding movements of the carriage is vertically adjustable at one end to vary the rate of feeding movements of the slide relative to the traveling movements of the carriage.

15. The invention as defined in claim 5, in 45 which the cam for controlling the feeding movements of the slide is made of two adjustably connected parts, one part determining the upper limits of movement of the slide and the other 50 part determining the lower limits of movement of the slide.

16. The invention as defined in claim 5, in which the cam for controlling the feeding movements of the slide is made of two adjustably 55 connected parts, one part determining the upper limits of movement of the slide and the other part determining the lower limits of movement of the slide, the last-named part being vertically adjustable relative to the carriage to vary the 60 lower limits of movement of the slide.

17. The invention as defined in claim 5, in which the cam for controlling the feeding movements of the slide is made of two adjustably connected parts, one part determining the upper 65 limits of movement of the slide and the other part determining the lower limits of movement of the slide, the last-named part being vertically adjustable relative to the carriage to vary the lower limits of movement of the slide, and the 70 part which controls the upper limits of movement of the slide being longitudinally adjustable relative to the carriage to vary the point in the operations of the machine at which the slide reaches its upper limits of movement.

18. In a tapping machine, the combination of a work-holder; a tool-holder; a tool driving shaft; a pinion on said shaft; a carriage mounted to reciprocate in a plane intersecting the axis of said shaft; a rack on said carriage engaging and driving said pinion; reversible power means connected to said carriage to reciprocate the same; and means including means traveling with said carriage, for automatically reversing the action of the power means at the ends of travel of the carriage.
19. In a tapping machine, the combination of a work-holder; a tool-holder; a tool driving shaft; a pinion on said shaft; a carriage mounted to reciprocate in a plane intersecting the axis of said shaft; a rack on said carriage engaging and driving said pinion; reversible power means connected to said carriage to reciprocate the same; and means, including means traveling with said carriage, for automatically stopping and reversing the action of the power means at the ends of travel of the carriage, said last-named means comprising adjustable devices, one mounted at each side of the carriage and each adjustable along the carriage to vary the points in the travel of the latter at which its movement is stopped and caused to reverse.
20. In a tapping machine, the combination of a frame; a tool-holder; a work-holder; means for producing relative feeding movements of the tool-holder and work-holder toward and from each other including a slide on which one of said holders is mounted; a carriage mounted to travel at right angles to the direction of movement of the slide; a cam on the carriage engaging the slide to control the feeding movements of the latter; a double acting fluid operated motor for reciprocating said carriage; means, including a reversing valve and operating means therefor, in part mounted on the carriage and in part mounted on the frame, for controlling the direction and extent of operation of the carriage; and means for relieving the pressure of the fluid on one side of the motor during the reversing operation thereof.

engaging the slide to control the feeding movements of the latter; reversible power means connected to said carriage to reciprocate the same; and means, including means traveling with the carriage, for controlling the direction and extent of operation of the carriage.

21. In a tapping machine, the combination of a frame; a tool-holder; a work-holder; means for rotating said tool-holder; means for indexing the work-holder to bring pieces of work successively into position to be operated upon by a tool in the tool-holder; and fluid operated means for supplying power to and rotating said rotating means and operating said indexing means alternately and in coordination.

22. In a tapping machine, the combination of a frame; a tool-holder; a work-holder; means for producing relative feeding movements of the tool-holder and work-holder toward and from each other including a slide on which one of said holders is mounted; a carriage mounted to travel at right angles to the direction of movement of the slide; a cam on the carriage engaging the slide to control the feeding movements of the latter; a double acting fluid operated motor for reciprocating said carriage; means, including a reversing valve and operating means therefor, in part mounted on the carriage and in part mounted on the frame, for controlling the direction and extent of operation of the carriage; and means for relieving the pressure of the fluid on one side of the motor during the reversing operation thereof.

ERIC J. STAHLHAMMER. 35
